UNITED STATES PATENT OFFICE.

ANNA M. NELSON, OF PORTLAND, OREGON.

GAME.

Application filed March 9, 1925. Serial No. 14,038.

To all whom it may concern:

Be it hereby known that I, ANNA M. NELSON, a citizen of the United States, and a resident of Portland, in the county of Multnomah and State of Oregon, have invented 5 a new and useful Game, of which the following is a specification.

This invention relates generally to games for providing amusement, and particularly 10 to a game board which can be used in competitive matches in which the skill of one player can be pitted against that of another.

The first object of this invention is to 15 provide an exceedingly simple, efficient and inexpensive form of amusement in which two players can oppose each other in a contest of skill and watchfulness.

The second object is to so construct the 20 game that one player will be on the offensive during one period of the play and on the defensive during the next period, and so on.

The third object is to provide two kinds 25 of movable objects or pawns, one kind representing sheep, which are in the majority and somewhat limited in their power to move, and incapable of capturing an opponent; while the other kind represents a 30 pack of wolves, less in number than the sheep but having greater powers of movement, and being able to capture sheep under certain conditions.

The fourth object is to so construct the 35 game that it cannot be wilfully blocked or its progress delayed for any appreciable amount of time by either player.

These, and other objects, will become more 40 apparent from the specification following as illustrated in the accompanying drawing, in which:

Figure 1 is a front elevation of the game board of which Figure 2 is a plan showing 45 the position of the animals at the start of the game. Figure 3 illustrates the position which the opposing sides can take, in which the sheep have started down one side of the board and are having their progress blocked by a wolf, and a second wolf has threatened 50 the lives of three sheep, necessitating a protective move on the part of the sheep. Figure 4 shows the game in a further state of progress, in which the wolves make the next move, and in which one or two sheep 55 will be lost. Figure 5 shows a possible condition at the close of one period of play in

which five sheep have successfully reached the sheep fold.

Similar numbers of reference refer to the same parts throughout the several views. 60

Referring in detail to the drawing, the game itself is preferably made in the form of a square board 10 in which are formed the holes 11 to 59 inclusive. Lines 60 passing through the holes 11 to 59 parallel to the edges of the board are painted thereon, and are the sheep trails. Diagonal lines 61 perpendicular to each other pass through the center of the board through the hole 35, 65 and their ends terminate in the holes 11, 17, 53 and 59. Other diagonal lines 62, 63, 64 and 65 parallel and perpendicular to the lines 61, intersect the lines 61 and extend between the holes 14, 32, 56 and 38. The points of intersection of the lines 61 with the lines 62 to 65 are marked with holes 66, 70 67, 68, and 69.

Twenty-one short round-headed pegs 70 to 90 inclusive, representing sheep, are provided, as well as three tall square-headed pegs 91, 92 and 93, representing wolves. 80

In order that the principle of the game may be better understood its governing rules will first be given as follows: The sheep can only travel along their paths which are the lines 60 running parallel to the edges of the board 10, but cannot move backwardly toward their starting point, although they can move laterally in either direction as often as desired. They can move one hole 90 at a time and cannot jump an opponent. Their sole object is to reach the sheep fold, which is the line 60 at the further side of the board. 95

The wolves can travel in the sheep trails 60 or the wolf trails 61, 62, 63, 64 or 65, going one space at a time along any of the lines, unless they are jumping, or when crossing the intersection of the lines 61 with the lines 62 to 65 inclusive. In other words, 100 a wolf, for instance, may travel in one move from the hole 40 to the hole 69 or the hole 50, provided the latter is not occupied, in which case it would only be possible to move 105 to the hole 69. Any of the wolves can jump one or more sheep if the hole beyond the sheep is not occupied by another sheep or another wolf.

In order to prevent any of the wolves 110 from occupying a hole in the sheep fold for an undue amount of time their stay therein is limited to two moves—that is, one each

2
by the remaining wolves or two by one of the wolves, after which the wolf in the sheep fold must again move out, although he can again return to the fold if desired.

5 After a sheep has reached the fold it is privileged to move in any direction along the sheep trails 60. The number of sheep entering the fold—that is, the total of the sheep in the outer row or the sheep fold, 10 plus any full row and the next part row ahead of it, will constitute the amount scored. Of course if the first row is not completely filled, the score will be the number of sheep in that row; the period not 15 being concluded until all of the sheep are either in the fold or captured.

The operation of the game is as follows: The sheep and wolves are placed on the board, as indicated in Figure 2, and an 20 opening made by the sheep and wolves moving to the position shown in Figure 3. It will be seen in Figure 3 that the sheep 89 and 88, as well as the sheep 86, are now in peril from the wolf 93, who can capture all 25 three of the sheep in a triple jump from the hole 56 through the holes 68, 35 and 67 in succession. It therefore becomes necessary for the player in charge of the sheep to so move same that this will not be possible, 30 or that the amount of sacrifice is reduced.

In Figure 4 the positions have become still more complicated, some the sheep having worked their way to the fold while some are on their way under protection of each 35 other, while still others are easy prey to the wolves.

In Figure 5 it will be seen that all of the sheep but five have been captured; this representing the score to be credited to the

shepherd or player for the period. The 40 players now reverse sides and the game is finished at the close of the second period in favor of the player having the greatest number of sheep enter the fold. In case of a 45 tie two more periods must be played.

I am aware that other games employing boards having holes provided therein in which pegs are moved about and players captured have been constructed in the past. I therefore do not intend to cover such a 50 game broadly, but I do intend to cover all such forms and modifications as fall fairly within the appended claim.

I claim:

A board having a plurality of spaced cross 55 lines representing sheep trails perpendicular to each other formed thereon; a hole formed in said board at each intersection of said cross lines; said board having diagonal lines 60 formed across same joining its corner holes, said diagonal lines representing wolf trails said board also having a second set of diagonal lines joining the middle holes in each outer row with the middle holes of adjacent rows of holes, said last mentioned lines 65 also representing wolf trails, each intersection of both sets of wolf trails being marked with a hole not on one of the sheep trails; a plurality of pegs representing sheep permitted to travel along said sheep trails only; and a plurality of pegs representing wolves 70 permitted to travel along said sheep trails or said wolf trails and to capture said sheep by jumping over same into an unoccupied hole in the same straight line next adjacent 75 to said sheep.

ANNA M. NELSON.
